Primary Examiner — Karen S Acker(74) *Attorney, Agent, or Firm* — William E. Gallagher;
Richard L. Alexander**CLAIM**

The ornamental design for sheet material for an absorbent article, as shown and described.

DESCRIPTION

FIG. 1 is a front view of sheet material for an absorbent article, embodying our new design; and,

FIG. 2 is a front view of the second embodiment of sheet material for an absorbent article, embodying our new design.

1 Claim, 4 Drawing Sheets(56)
